DESIGN FOR A GAME BOARD

Le Roy Heflin and Katherine M. Skuderna,
Rocky Ford, Colo.

Application December 29, 1939, Serial No. 89,211

Term of patent 7 years

To all whom it may concern:

Be it known that we, Le Roy Heflin and Katherine M. Skuderna, citizens of the United States of America, residing at Rocky Ford, in the county of Otero and State of Colorado, have invented a new, original, and ornamental Design for a Game Board, of which the following is a specification, reference being had to the accompanying drawing, forming part thereof.

We claim:

The ornamental design for a game board, as shown.

LE ROY HEFLIN.
KATHERINE M. SKUDERNA.
